UNITED STATES PATENT OFFICE

JOSEPH TAYLOR, OF CHICAGO, ILLINOIS, ASSIGNOR TO GRIGSBY-GRUNOW COMPANY, OF CHICAGO, ILLINOIS, A CORPORATION OF ILLINOIS

DESIGN FOR A RADIOCABINET

Application filed January 30, 1933. Serial No. 47,057. Term of of patent 7 years.

To all whom it may concern:

Be it known that JOSEPH TAYLOR, a citizen of the United States of America, residing at Chicago, in the county of Cook and State of Illinois, has invented a new, original, and ornamental Design for Radio Cabinets, of which the following is a specification, reference being had to the accompanying drawing, forming part thereof.

Figure 1 is a perspective view of the cabinet with the cover closed; and

Figure 2 is a perspective view with the cover open.

I claim:

The ornamental design for a radio cabinet as shown.

In testimony whereof he affixes his signature.

JOSEPH TAYLOR.
